(57) **CLAIM**

(21) Appl. No.: **29/105,021**

The ornamental design for “female member of snap button for wear,” substantially as shown and described.

(22) Filed: **May 14, 1999**

DESCRIPTION

(30) **Foreign Application Priority Data**

FIG. 1 is a front view of a female member of snap button for wear showing our new design;

Dec. 25, 1998 (JP) 10-38349

FIG. 2 is a top plan view thereof;

(51) LOC (7) Cl. **02-07**

FIG. 3 is a right side view thereof;

(52) U.S. Cl. **D11/220**

FIG. 4 is an enlarged cross sectional view along line 4—4 of FIG. 3; and,

(58) Field of Search D11/200-220,

FIG. 5 is an enlarged cross sectional view along line 5—5 of FIG. 3.

D11/231; 24/303, 66.1, 201; D8/382, 349,
354, 373

The drawings show a part of the female member, and the female member is continuous longitudinally only.

Its rear view should be symmetrical with the front view, its left side view should be symmetrical with the right side view, and its bottom plan view should be identical with the top plan view.
